UNITED STATES PATENT OFFICE.

ALBERT ALFRED MEAD, OF LONDON, ENGLAND, ASSIGNOR TO MEAD, MCLEAN & COMPANY LIMITED, OF LONDON, ENGLAND, A CORPORATION OF GREAT BRITAIN.

VENTILATOR FOR RAILWAY AND OTHER VEHICLES.

Application filed February 14, 1929, Serial No. 339,833, and in Great Britain December 8, 1927.

This invention comprises improvements in and connected with ventilators for railway and other vehicles, and is concerned with ventilators of the louvre type. These ventilators sometimes comprise louvre plates of glass but such plates may be of metal or other material where the transparency and attractive appearance of glass are not important considerations. The louvre plates 5 are supported vertically by swivel shoes which are simultaneously operated by a horizontally movable bar or the like. The adjustment of this bar swivels the plates to set the latter in an angular position in which 10 they may be outwardly inclined in either direction to a desired degree. Thus, these louvre ventilators may be set either for extraction or for injection of air according to the direction of their inclination with reference to the direction of travel. In the closed 15 condition of ventilators of this type, the louvre plates are all set in one and the same plane and vertical edges of neighbouring plates are as close together as possible. Nevertheless, air, rain, moisture, dust and so on 20 may be forced through the chinks or narrow apertures between the louvre plates. For this reason, it has been proposed to provide a covering device movable out of a closed position in one plane to an open position in another plane upon opening the louvre, the said device being closed under spring action upon 25 the closing of the louvre.

The object of this invention is to provide 30 a louvre ventilator of this type with a simple mechanism adapted for positively adjusting the covering device to a closed position when the louvre ventilator is adjusted to its closed position and for positively adjusting the covering device to an open position 35 when the louvre ventilator is adjusted to an open condition of any desired degree in either direction.

In order to enable the invention to be 40 readily understood, reference is directed to the accompanying drawing in which:—

Figure 1 illustrates one form of ventilator in elevation together with distant operating 45 means therefor.

Figure 2 shows the same ventilator in plan.

Figure 3 is a section along the line III—III of Figure 1 looking upwards in the direction of the arrows. 55

Figure 4 is a cross-section of Figure 1.

Figure 5 is a fragmentary view showing modified louvres applicable to constructions such as are seen in Figures 1 to 4 as will be hereinafter described. 60

Figure 6 is a view similar to Figure 4 of a second form of ventilator in accordance with this invention.

Figure 7 is a central horizontal section, similar to Figure 3, of another form of ventilator and. 65

Figure 8 is a transverse section of such ventilator.

In the construction illustrated by Figures 1 to 4, the ventilator comprises an open oblong casing or framing *a* provided in one open face with vertical louvre plates *b* and in its opposite open face with horizontal louvre plates *c*. *d* represents part of the vehicle door or wall in which the ventilator is 70 mounted with the vertical louvres on the inside and the horizontal louvres outside. The louvre plates *b* and *c* may be glass strips, as shown, having swivel shoes *e*, *f* respectively, secured to their ends. The pivots *g* of the 75 swivel shoes *e* of the vertical louvre plates are received in bearings provided along the top and bottom longitudinal bars of the casing or framing *a* at one side thereof. The pivots *h* of the swivel shoes *f* of the horizontal louvre plates are received in bearings 80 provided down the edges of the vertical bars of the casing or framing *a* at the opposite sides of the latter. The number of vertical louvre plates may, as shown, be greater than 85 the number of horizontal louvre plates. 90

The swivel shoes *e* at one end of the vertical louvre plates are formed or fitted with lugs or arms *k*, Figures 3 and 4, which extend inwardly of the casing or framing *a*, 95 and such arms have pivotal connection at *l* with a bar *m* which is shiftable endwise and has a parallel ruler motion owing to its pivotal connection with the several swivel shoes. 100 Usually, and as shown, this bar *m* is disposed

in the top longitudinal member of the framing so that it is the top swivel shoes that are provided with the arms *k* for pivotal connection with the bar.

5 The swivel shoes *f* at one end of the horizontal louvre plates *c* are formed with arms or lugs *n* also extending inwardly of the casing or framing *a* and such arms have pivotal connection at *o* with a short bar *p* movable 10 endwise up and down against one of the side walls of the casing.

The vertical louvre plates *b* are so dimensioned and disposed that in their closed position, they are all edge to edge in one 15 and the same plane as aforesaid and as will be seen from Figures 1 and 3. Thus they can be adjusted to any angle of inclination in either direction as already explained. The horizontal louvre plates *c* are also preferably so dimensioned and disposed on their pivots *h* that in their closed position they come into the same plane as seen in Figures 20 3 and 4. The horizontal louvres can be turned upwardly to an open position shown, for example, by dotted lines in Figure 4 25 and downwardly to a closed position. One of the swivel shoes *f* or lugs *n* of the top horizontal louvre plate is formed or fitted with a projection such as *r* which is suitably 30 rounded and that end of the horizontally movable bar *m* which is adjacent to such shoe is formed or fitted with a longitudinally slotted projection *s*, Figure 3. On the underside of the top member of the casing 35 *a* there is pivoted a lever *t* extending longitudinally of the casing from its pivot *u* towards the adjacent end of the casing. This lever is provided intermediately with a downwardly projecting pin *v* taking into 40 the longitudinal slot of the bar *m*. The end of such lever is provided with a fork *w* 45 for engaging with the projection *r* on the swivel shoe aforesaid of the upper horizontal louvre.

45 In the closed condition of the ventilator, the horizontally movable bar *m* occupies a mid-position longitudinally but an outward position (as compared with the vehicle) laterally of the frame *a* as seen in Figure 3. Longitudinal movement of this bar in either 50 direction from this mid-position causes the vertical louvre plates *b* to be swivelled one way or the other and to acquire an angular setting in one sense or the other in relation to the direction of travel of the vehicle. The bar will also move bodily, laterally, owing to the parallel-roller motion, but such lateral movement will be always 55 in the same direction, inwardly, from the above-mentioned outward position. Consequently any movement of the bar *m* will, as regards the longitudinal component, merely cause the slotted part *s* to slide past the pin *v* of the lever *t* in one direction or 60 the other. As regards the lateral compo-

nent, however, the slotted part will draw the pin *v* and, therefore, the lever *t* laterally and thus inwardly as compared with the vehicle. This movement of the lever *t* is communicated through its work *w* to the projection *r* aforesaid, thereby swivelling the shoe of the top horizontal louvre plate *c* and causing the latter to turn upwardly and outwardly. Owing to the inter-connection of the horizontal louvre plates *c* by the bar *p* as aforesaid, they are all moved simultaneously and similarly, as indicated by the dotted lines in Figure 4, so that opening of the vertical louvre plates *b* in either direction brings about an opening so movement of the horizontal louvre plates *c*.

The bar *m* may be operated in any suitable manner and by way of example a Bowden wire or like flexible control is illustrated in Figures 1 and 2. At either end the bar *m* has upwardly extending pins or studs *x* *x'* passing through slots *y* *y'* in the upper bar of the casing *a* and connected to respective flexible wires *z* *z'* of the control. The posts 1 fixed on the top bar of the frame or casing *a* are for anchoring the casings or sheaths of the flexible transmission wires *z*, *z'*. Operation of the wires is by a lever 2 which may be situated in any convenient position in the vehicle. In the central position of the operating lever, seen in Figure 1, the ventilator is closed. On movement of the lever to either side of this position the bar *m* is moved to open the ventilator. The slots *y*, *y'* aforesaid would have to be of curved form to conform to true parallel-ruler movement of the bar *m* but for the sake of simplicity they may be made of V form as shown and the lugs *k* of the upper swivel shoes of the vertical louvres *b* slotted as at 3 (Figure 3) where they engage the pins *l* to allow of the slight departure from true parallel-ruler motion. The slots *y*, *y'* not only impart guidance to the bar *m* but they also have a camming action on the bar to impart lateral movement to it positively and, in conjunction with the slots 3, relieve the swivel shoes and pivots *g*, *l* of the vertical louvres *b* of strain (which they might otherwise have to bear) involved in operating the horizontal louvres *c*. The flexible transmission may be wholly enclosed if desired, within the wall paneling of the vehicle and only the operating lever 2 be visible and accessible.

The horizontal louvre plates *c* may be adapted to overlap one another slightly in the closed position. For example, they may be formed with bevelled edges which overlap when the plates are moved to the closed position as seen in Figure 4. Having regard to the fact that air or matter has only very limited access when the vertical louvre plates *b* are closed, the further protection

afforded by overlapping bevelled edges of the horizontal louvre plates *c* renders the entry of air or matter into the interior of the vehicle practically impossible. As an alternative to the bevelling of the edges, and as indicated in the fragmentary view, Figure 5, each of the horizontal louvre plates *c* may be fitted along one edge with a strip 4 of metal, wood, rubber or other material, designed to overlap the edge of a neighbouring plate in the closed condition and to seal any slit or chink that may exist between such plates.

It will be apparent that other mechanisms or mechanical motions than that described may be adopted for securing co-ordinated movements of the two sets of ventilator devices *b*, *c*. Also that the movements in the particular mechanism above described may be modified to suit requirements as by giving a suitable inclination or cam-shape to the slot of the slotted part *s* of the bar *m*.

As a modification of the above described ventilator, instead of a horizontal louvre device comprising a plurality of louvre plates, a simple flap or single louvre plate may be employed. This is illustrated by way of example in Figure 6 in which a single flap 5 of framed glass is hinged at the upper edge at 6 along the upper longitudinal edge of the frame or casing *a* and adapted to be opened and closed by a lever 7 mounted by means of pivot 8 along one side of the ventilator frame. In other respects the ventilator is similar to that shown in Figures 1 to 4. In Figure 6, the fork *w* engages a pin 9 on the upper end of the lever 7 and the lower end of the lever is connected by pin and slot with an arm 10 fixed to the frame of the flap 5. Thus when the vertical louvre plates *b* are moved to the open position in either direction the flap 5 will also be opened, as shown for example, by dotted lines, and when the vertical louvre plates are moved to the closed position the flap 5 will be positively closed. The frame of the flap is recessed around the edge to receive a packing 11 for sealing the flap against the outer edge of the frame or casing *a* in the closed position.

In the construction shown in Figures 7 and 8, the cover device consists of an open angle iron frame 12 in which is hingedly mounted a window 13, and this cover device is movable bodily away from the casing *a* to the open position seen in dotted lines in Figure 8. The bar *m* pivotally connected with the shoes of the louvre plates *b* is, in this case, fitted with two plates 14 having slots 15. Angle levers 16 secured intermediately to pivot pins 17, have pins on their short arms engaging in the slots 15. At the end of its long arm one of the levers 16 is connected by a link 18 with a lug 19 at one top corner of the angle frame 12 the

corresponding end of the other arm of the other lever being connected directly to a lug 19^a at the other top corner of the frame. The pivot pins 17 extend from top to bottom of the casing and turn in suitable bearings. At their lower ends, the pins 17 have fixed to them lever arms 16^a which are similar to the long arms of the levers 16. These arms 16^a are connected with the bottom corners of the frame 12 in a manner similar to the upper arms 16. It will now be seen that when the bar *m* is moved in either direction for opening the louvre *b*, the resultant lateral movement of such bar will rock the levers 16 and lever arms 16^a to move the cover device 12, 13 bodily away from the seating 11. Movement of the bar *m* to close the louvre *b* will operate the levers 16, 16^a reversely so that the cover device will be drawn powerfully at all four corners to the closed position against the seating 11. The window 13 is hingedly mounted in the frame 12 so that it can be opened to give access to the louvre plates *b* for cleaning and to the mechanism for lubrication or adjustment.

It will be appreciated that in any of the constructions described, the space within the casing between the two ventilator parts need only be shallow from front to back. As matter may be deposited in this space within the casing, cleaning holes may be formed in the latter if desired for enabling such matter to be removed, as indicated by way of example at 21, in Figure 4. Facility for cleaning the glass surfaces within the casing, may be provided for by dividing the frame in a plane parallel with its front and back faces and these divided parts may be hingedly connected along one side as shown by way of example at 22 in Figure 6 and fitted with locking means 23 at the opposite side. To allow of the hinging, the lever *t* could be removed or loosened on its pivot *u* so as to disconnect the operating mechanism of the two parts of the ventilator as will be readily understood.

I claim:—

1. Vehicle ventilator comprising in combination a reversible louvre device, a cover device adapted to be opened by moving it out of its plane of closure, and interconnecting mechanism operating positively both to open said cover device when said reversible louvre is opened and to close said cover device when said reversible louvre is closed.

2. Vehicle ventilator comprising in combination a reversible louvre device, a cover device adapted to be opened by moving it out of its plane of closure, a bar having pivotal engagement with swivel members of the louvre device, a lever system operatively connected with said bar, and an operative connection between said lever system and

said cover device to positively open and close the latter.

3. Vehicle ventilator comprising in combination a reversible louvre device, a cover device adapted to be opened by moving it out of its plane of closure, interconnecting mechanism operating to ensure simultaneous opening or closing movements of said louvre and said cover device, a manual control means, and a flexible transmission between said control means and said mechanism.

4. Vehicle ventilator comprising in combination a reversible louvre device, a cover device adapted to be opened by movement bodily away from its plane of closure, and a plurality of lever systems inter-connecting said louvre and cover devices and operative for positively opening or closing said cover device simultaneously with opening or closing of said reversible louvre.

5. Vehicle ventilator comprising in combination a reversible louvre device, a cover device adapted to be opened by movement bodily away from its plane of closure, a slideable bar having pivotal engagement with the swivel shoes of the louvre, and a plurality of lever systems having pin and slot engagement with said bar and operative connection with points distributed over said cover device substantially as set forth.

6. Vehicle ventilator comprising a fixed ventilator casing, a reversible louvre device therein, a cover device adapted to be opened by moving it out of its plane of closure, a bar having pivotal engagement with swivel members of the louvre device, a lever system operatively connected with said bar, an operative connection between said lever system and said cover device whereby the latter is positively opened or closed when the louvre device is opened or closed, and guiding means in the fixed ventilator casing for said bar substantially as set forth.

7. Vehicle ventilator comprising an open framing, a reversible louvre adapted for closing one side of said framing, a cover device closable against the opposite side of said framing and movable away from said side to open, a bar slideable along and laterally of said framing and having pivotal connection with swivels of said louvre, and lever mechanism influenced by lateral movement of said bar and operatively connected with said cover device to produce positive opening or closing of the latter as said louvre opens or closes substantially as set forth.

8. Vehicle ventilator comprising an open framing, a reversible louvre adapted for closing one side of said framing, a cover device closable against the opposite side of said framing, a bar slideable along and laterally of said framing and having pivotal connection with swivels of said louvre, lever mechanism influenced by lateral movement of said bar and operatively connected with

said cover device to produce positive opening or closing of the latter as said louvre opens or closes, a manual control, and a Bowden wire transmission between said control and opposite ends of said bar substantially as set forth.

ALBERT ALFRED MEAD.
